UNITED STATES PATENT OFFICE.

ALVAH C. ROEBUCK, OF WOODSTOCK, ILLINOIS, ASSIGNOR TO WOODSTOCK TYPEWRITER COMPANY, OF WOODSTOCK, ILLINOIS, A CORPORATION OF ILLINOIS.

MARGIN-STOP INDICATOR.

1,256,595.

Specification of Letters Patent. Patented Feb. 19, 1918.

Application filed May 19, 1915. Serial No. 29,062.

To all whom it may concern:

Be it known that I, ALVAH C. ROEBUCK, a citizen of the United States, residing at Woodstock, in the county of McHenry and 5 State of Illinois, have invented certain new and useful Improvements in Margin-Stop Indicators, of which the following is a specification.

This invention relates to typewriters, and 10 more particularly to the margin stop mechanism. The present invention is to provide an improved construction, combination and arrangement of parts by means of which the position of the margin stop may be easily 15 ascertained by an operator from the front of the typewriter.

Other objects will appear hereinafter.

In the accompanying drawings, Figure 1 shows a view, partly in section, of that portion 20 of a typewriter to which the present invention is applied, with a margin stop indicator constructed in accordance with the principles of this invention; Fig. 2 is a top view of the margin stop indicator; and Fig. 25 3 is a side elevation of the same.

When the margin stop mechanism is located at the rear of the typewriter, it is invisible to an operator at the front of the typewriter for the reason that it is mounted 30 at the lower rear side of the carriage behind the platen and below the paper table. For this reason it cannot be conveniently adjusted by an operator from the front of the typewriter without rising from 35 his seat or going to the rear of the machine. The present invention overcomes this difficulty by providing an indicator arm in connection with the margin stop proper and an indicator bar at the upper portion of the 40 shiftable frame, both of which are clearly visible from the front of the machine when the shift frame is in any position, by simply rotating the paper table at its pivot.

In the drawings, the numeral 4 designates 45 generally that portion of a typewriter frame in which a carriage 5 is mounted by means of ordinary ways 6. Mounted in the carriage is a shift frame having an end piece 7 at each end in which a platen 8 is rotatably 50 mounted and a paper table 9 is pivoted in such position that it may be rotated against the platen, as indicated by the dotted outline in Fig. 1. The shift frame is oscillated by means of a shift bar 10 in any well known 55 manner.

Secured in the carriage is a margin stop bar 11 and secured in the shift frame and forming a part thereof is a graduated bar 12 which is parallel to the margin stop bar preferably directly above it and at the rear 60 of the paper table 9 where it constitutes a stop for the table limiting the rearward movement thereof. The margin stop bar 11 is usually close to the frame 4 at the rear of the carriage behind the platen 8 and below 65 the paper table where it cannot be easily seen from the front of the machine. The graduated bar 12 being located above the margin stop bar 11 and in the shift frame is plainly visible from the front of the machine 70 when the paper table is rotated against the platen and this bar is graduated on top so that the graduations are visible and readable from the front of the typewriter.

Mounted on the margin stop bar 11 is a 75 margin stop 13 provided with a pivoted catch 14 by means of which the position of the margin stop may be adjusted along the bar, the bar being commonly provided with notches or teeth 15 which are engaged by the 80 pivoted catch 14. Secured to the margin stop 13 is an arm or indicator 16 preferably formed of metal and of such a length that it extends above the indicator bar 12 when the shift frame is in its lowermost 85 position and sufficiently above it to be clearly visible from the front of the typewriter when the shift frame is raised, as shown by the dotted outline in Fig. 1. The arm, however, is not sufficiently long to engage the paper table 9 at any time and it offers no obstruction nor does it engage with the indicator bar 12, but simply lies adjacent the graduated edge of the bar so that the 90 position of the margin stop is clearly visible 95 from the front of the typewriter when the paper table is rotated against the platen. The margin stop may then be adjusted along the stop bar 11 by holding the paper table 100 forward with one hand and by simply placing the other hand over the platen and paper table and operating the catch 14 to disengage it from the bar 11 so that the margin stop may be freely moved to any desired 105 position, as indicated by the arm 16 with respect to the indicator bar 12.

What I claim is:

1. In a typewriter, a platen carriage, a paper table pivoted therein, a margin stop 110 adjustably mounted below the table, and an

upwardly extending indicator secured to the margin stop normally behind the table and invisible from the front of the typewriter and visible when the table is rotated forwardly on its pivots.

2. In a typewriter, a carriage, a platen pivoted in the carriage, a bar behind the platen, a margin stop adjustable in the carriage, an indicator extending upwardly from the margin stop, and a paper table pivoted between the bar and the platen and limited in movement in opposite directions by them, and normally covering the indicator but uncovering it when the table is rotated against the platen.

3. In a typewriter, a carriage, a platen and a paper table pivoted in the carriage, a bar behind the table graduated on top, a margin stop adjustably mounted below the said bar, and an indicator extending above and adjacent the bar normally carried by the table but visible from the front of the typewriter when the table is rotated forwardly.

25 4. In a typewriter, a stop bar, and a parallel graduated bar above it, a margin stop and an indicating arm extending adjacent the graduated bar, and a pivoted paper table normally covering the graduated bar and the said arm which are both within the vision of an operator at the front of the typewriter when the paper table is turned forwardly.

5. In a typewriter, a carriage, a frame 35 shiftable therein, a stop bar in the carriage, a graduated bar in the frame, a margin stop adjustable on the stop bar, an indicator arm extending from the stop to the side of the bar to show the position of the stop, and a

paper table pivoted in the frame normally covering the arm and the bar in any position of the frame but rotatable forwardly to uncover them for an operator seated at the front of the typewriter.

6. In a typewriter, the combination with 45 a carriage, of a margin stop adjustably mounted in the carriage having an extending indicating arm, a graduated indicator bar adjacent which the upper end of the arm extends, and a paper table pivoted adjacent the bar by which the movement of the table is limited in one direction.

7. In a typewriter, the combination with a carriage, of a shiftable frame mounted in the carriage, a stop bar fixed in the carriage, a graduated bar fixed in the frame, a paper table pivoted in the frame and movable against the graduated bar, the stop bar being below the paper table and invisible to the operator from the front of the typewriter and the graduated bar being visible from the front of the machine when the paper table is rotated therefrom, a margin stop adjustable on the stop bar, and an indicator arm extending from the margin stop 55 and at the side of the graduated bar to show the position of the margin stop with respect to the graduated bar regardless of the shifted position of the frame.

In testimony whereof I have signed my 70 name to this specification, in the presence of two subscribing witnesses, on this 12th day of May, A. D. 1915.

ALVAH C. ROEBUCK.
